UNITED STATES PATENT OFFICE

124,649

DESIGN FOR A GLASS JOINT MEMBER

Robert S. Fish, Corning, N. Y., assignor to Corning
Glass Works, Corning, N. Y., a corporation of
New York

Application February 26, 1940, Serial No. 90,507

Term of patent 14 years

To all whom it may concern:

Be it known that I, Robert S. Fish, a citizen
of the United States of America, residing at
Corning, in the county of Steuben and State of
New York, have invented a new, original, and
ornamental Design for a Glass Joint Member,
of which the following is a specification, refer-
ence being had to the accompanying drawing,
forming part thereof.

In the drawing:

The figure is a side elevational view of a glass
joint member showing my design.

The dominant features of my design reside
in the portions shown in full lines.

I claim:

The ornamental design for a glass joint mem-
ber, as shown and described.

ROBERT S. FISH.
